STARTING DEVICE FOR INTERNAL-COMBUSTION ENGINES.

1,227,688.

Specification of Letters Patent. Patented May 29, 1917.

Application filed November 20, 1916. Serial No. 132,260.

To all whom it may concern:

Be it known that we, ARTHUR L. STRAHLE, of Benson, in the county of Douglas and State of Nebraska, and HILAND B. NOYES, of Omaha, in the county and State aforesaid, citizens of the United States, have invented certain new and useful Improvements in Starting Devices for Internal-Combustion Engines, and have described the same in the following specification, illustrated by the accompanying drawings.

Our invention relates to that class of starting devices which are commonly employed in cranking the internal combustion engines of automobiles, and which individually comprise a cranking shaft for rotating the crankshaft of the engine, means for mutually connecting and disconnecting these shafts, a motor-driven shaft, and gearing between the motor-driven shaft and the cranking shaft. It is the main object of the invention to impart a resiliently yielding quality in a superior manner to the operative connection between the two last-mentioned shafts of a starting device of this class; to cushion the shock of impact as the cranking shaft rotarily engages the crankshaft; to cause the cranking motor, as it initiates the rotation of the engine, to take up its load in a gradual and progressive manner; to reduce to a minimum the requisite power and weight of this motor; to increase the durability of the apparatus; at the same time to provide for starting the engine with a hand crank, independently of the gears, whenever occasion may require; and in general to produce a superior and efficient starting device of the specified class. To accomplish these results, we incorporate in our improved starter, as parts thereof, a longitudinally slidable cranking shaft, a ratchet-wheel thereon, a pair of spiral gears between the motor-driven shaft and the cranking shaft, and a spring pawl operating between the ratchet-wheel and the gears.

In said drawings, illustrating the best manner in which we have contemplated applying the principles of the invention, Figure 1 is an axial vertical section, partly a side elevation, of a starting device which is constructed in accordance with these principles and is mounted in an operative position on an extension of the crank case of an automobile of familiar type. Fig. 2 is an incomplete vertical section on the section line 2-2 in Fig. 1, parts being broken away

to show internal construction. Fig. 3 is a plan of the gear case of the same starter, mounted as in Fig. 1.

In the instance illustrated by these drawings, the cranking shaft 1, disposed in axial alignment with the crankshaft 2, is journaled in the front end bearing 3 of the crankcase 4, by means of the bush 5, and is slidable longitudinally therein. In its forward end it has a pin 6 for engagement with a hand crank. On its rear end it carries the ratchet-toothed clutch member 7 for engagement with the similar clutch member 8 on the crankshaft; and in an intermediate location, forward of the bearing 3, it carries the keyed ratchet-wheel 9. The spiral gear 11 is rotatably mounted on the same shaft by means of the intermediate hub 10 of this ratchet-wheel; and is retained on this hub by the face-plate 12 fastened to the end of the hub by the screws 13. This gear is hollow, having the annular and externally grooved peripheral wall 14 which distantly encircles the contained ratchet 9. It contains a plurality of uniformly spaced spring pawls 15, duplicates of each other, working between the gear and the ratchet, and consisting severally of an arcuate strip of steel, of uniform section area, having one end rigidly secured to the inside of the wall 14, and the other end contacting with the periphery of the ratchet in an approximately tangential position.

The shaft 16, arranged in parallelism with the cranking shaft, and actuated by an unseen cranking motor, carries the fixed spiral pinion 17, which meshes constantly with the gear 11 within the gear-case 18. This gear-case has the ears 19 for mediate attachment to the frame of the vehicle. It has also the internally threaded cylindrical hub-like boss 20, axially aligned with the bearing 3 and clamped thereto by the prolonged bush 5, which is provided with the head 22 and external thread 21 and constitutes a tubular screw. In the cap 24, constituting the front wall of this gear-case, is formed the additional bearing 23 for the shaft 1; while the shaft 16 is journaled in both the front wall 105 and the rear wall of the same case.

Whenever the starting motor is brought into operation for the purpose of cranking the engine, the interaction of the spiral gears forthwith rotates the shaft 1 and also impels the same longitudinally backward, whereby the clutch members 7 and 8 are

brought into mutual engagement, and are rotated together until the engine begins to work. But as soon as this occurs, the clutch member 7 is kicked off from the quickened 5 clutch member 8 with a rotary tendency which impels the gear 11 to slide forward on the pinion 17 to its original position shown in Fig. 1; while the engine runs on, free of the starter, as the motor stops. Likewise 10 the teeth of the constantly meshing gears are so inclined that the axial thrust thereon holds the clutch members 7 and 8 in operative contact while the gears are being operated by the starting motor; and draws these 15 members apart when the speed of the gear 11 is accelerated by the starting of the engine. In this cranking operation, power derived from the motor is transmitted from the hollow gear to the contained ratchet- 20 wheel on the crankshaft by the endwise thrust on the described spring pawls 15, which are severally subjected thereby to longitudinal compression bending them to a greater or less curvature varying with the 25 resistance of the load. In overcoming the inertia of the engine and initiating the rotary movement of the crank shaft by the thrust of the elastically bending pawls, a brief instant of time is consumed, which is 30 of sufficient duration to reduce by a considerable and important percentage the requisite horsepower of the starting motor.

Without further explanation it is obvious that the described starter possesses the further merit of effecting the above specified 35 object of the invention in all other of the several particulars thereof which are above enumerated.

We claim as our invention—

40 1. A starting device of the specified class, comprising a crankshaft of an engine; a cranking shaft, movable both rotarily and endwise in its bearings; an independently rotatable spiral gear, mounted on the cranking shaft; a ratchet-wheel, fixedly mounted on the cranking shaft; a plurality of elastic pawls between the gear and the ratchet wheel; a motor-driven shaft carrying a spiral pinion meshing with the spiral gear; and means, operated by the cranking shaft, for coupling that shaft to the crankshaft of the engine.

45 2. A starting device of the specified class, comprising a crankshaft of an engine; a rotatable cranking shaft, slidable endwise in its bearings; a ratchet-wheel, having a hub keyed on the cranking shaft; an independently rotatable spiral gear wheel, mounted on the hub of the ratchet; a spring pawl 50 between the gear and the ratchet-wheel; a power-driven shaft carrying a spiral pinion meshing with the spiral gear; and coupling means between the cranking shaft and the engine crankshaft.

55 3. A starting device of the specified class,

comprising a crankshaft of an engine; a rotatable cranking shaft, slidable endwise; an independently rotatable spiral gear mounted on the cranking shaft; means for making and unmaking resiliently yielding 70 driving engagements between the cranking shaft and the spiral gear; a power-driven shaft carrying a spiral pinion meshing constantly with the spiral gear; and a ratchet clutch between the cranking shaft and the 75 crankshaft of the engine.

4. A starting device of the specified class, comprising a crankshaft of an engine; a cranking shaft, adapted to be rotated and slid endwise in its bearings by a terminal 80 hand crank; an independently rotatable spiral gear mounted on the cranking shaft; means for rotating the cranking shaft by the spiral gear; a power-driven shaft carrying a spiral pinion meshing with the spiral 85 gear; and means operated by the endwise movements of the cranking shaft for connecting that shaft with the crankshaft of the engine.

5. A starting device of the specified class, 90 comprising a crankshaft of an engine; a cranking shaft slidable endwise in its bearings; an independently rotatable spiral gear mounted on the cranking shaft; intermediate yielding means for driving the cranking 95 shaft by the gear; a motor-driven spiral pinion meshing constantly with the spiral gear; and a clutch, operated by the endwise movements of the cranking shaft, for coupling and uncoupling the crankshaft of the 100 engine and the cranking shaft.

6. A starting device of the specified class, comprising a crankshaft of an engine; a cranking shaft for rotating the crankshaft of the engine; means for mutually connecting and disconnecting these shafts; a power-driven gear rotarily mounted on the cranking shaft; and a resilient member through 105 which rotary power is transmitted from the gear to the cranking shaft.

7. A starting device of the specified class, comprising a crankshaft of an engine; a cranking shaft for rotating the crankshaft of the engine; means for moving the cranking shaft longitudinally in its bearings; 115 means for mutually connecting and disconnecting the shafts; a power-driven shaft; and an elastically yielding member for transmitting rotary power from the driven shaft to the cranking shaft.

8. A starting device of the specified class, comprising a crankshaft of an engine; a rotatable cranking shaft, slidable endwise; an independently rotatable gear mounted on the cranking shaft; means for making and 125 unmaking resiliently yielding rotative engagements between the gear and the cranking shaft; means for moving the shaft and gear rotarily and endwise; and means operated by endwise movements of the crank- 130

ing shaft for connecting that shaft with the crankshaft of the engine.

9. A starting device of the specified class, comprising a crankshaft of an engine; a 5 rotatable cranking shaft, movable endwise in its bearings; an independently rotatable spiral gear, mounted on the cranking shaft; a ratchet-wheel fixedly mounted on the cranking shaft; a pawl between the gear and the ratchet-wheel; a driven shaft carrying a spiral pinion meshing with the spiral gear; and opposing clutch members having ratchet teeth and carried by the cranking shaft and the crankshaft of the engine respectively.

10. A starting device of the specified class,

comprising a crankshaft of an engine; a rotatable cranking shaft, slideable endwise in its bearings; a ratchet-wheel having a hub keyed fixedly on the cranking shaft; an 20 independently rotatable spiral and hollow gear wheel, mounted on the hub of the ratchet-wheel; a plurality of arcuate spring pawls, secured to the inside of the hollow gear wheel; a power shaft carrying a spiral 25 pinion meshing with the spiral gear; and means for operatively connecting the cranking shaft with the crankshaft of the engine.

Witness our signatures, at Omaha, Nebraska, November 16th, 1916.
